UNITED STATES PATENT OFFICE.

WARREN W. ANNABLE, OF GRAND RAPIDS, MICHIGAN, ASSIGNOR TO THE STARTER MANUFACTURING COMPANY, OF GRAND RAPIDS, MICHIGAN, A CORPORATION OF MICHIGAN.

ELECTRICALLY-OPERATED VALVE.

936,074.

Specification of Letters Patent.

Patented Oct. 5, 1909.

Application filed April 26, 1909. Serial No. 492,114.

To all whom it may concern:

Be it known that I, WARREN W. ANNABLE, a citizen of the United States of America, residing at Grand Rapids, in the county of Kent and State of Michigan, have invented certain new and useful Improvements in Electrically-Operated Valves; and I do hereby declare the following to be a full, clear, and exact description of the invention, such as will enable others skilled in the art to which it appertains to make and use the same.

My invention relates to improvements in electrically operated valves, and more particularly to such valves adapted to control the admission of compressed fluid to the cylinders of an internal combustion engine, in starting the same, and its object is to provide the device with means for preventing intake of air through the device during the inspiration stroke of the engine; to provide release for the compression in the cylinders during the compression stroke of the same; and to provide the device with various new and useful features hereinafter more fully described and particularly pointed out in claims, reference being had to the accompanying drawings, in which:

Figure 1. is a side elevation of a device embodying my invention; Fig. 2. a vertical section of the same through the axis thereof; Fig. 3. a plan view of the same; Fig. 4. a horizontal section on the line 4—4 of Fig. 2; and, Fig. 5. an inverted plan view.

Like numbers refer to like parts in all of the figures.

1 is an induction magnet having an axial opening therethrough and provided with an exciting coil 2 embedded therein and surrounded by insulating materials 3.

5 are binding screws to which electric conductors are attached, whereby the coil is provided with an electric current to excite the magnet at proper intervals.

45 6 are insulating plugs in which the terminals are mounted, and 7 the respective ends of the coil 2 engaging the insulated binding screws 5.

In the axis of the magnet is a longitudinally movable bolt 8 having a valve 8^a at one end engaging an elastic valve seat 9 to control the flow of air therethrough. The magnet is provided with a boss 1^a surround-

ing this valve and adapted to communicate with any convenient supply pipe, to bring fluid under pressure to the device. The elastic seat 9 is held in place within this boss by a ring or bushing 10^a. On the opposite end of the bolt 8 is a disk armature 4 normally spaced apart a suitable distance from the magnet by a spring 15, which spring also holds the valve 8^a closed. This armature is adjustable on the bolt 8 by a screw thread, and to prevent change of adjustment, the end of the bolt is provided with a slot in which is 65 a spring arm 19 secured to the armature by a screw 20, thus when the arm is in the slot, the bolt can not turn in the armature to change its adjustment. In the side of the boss is an opening 10 in which is inserted 70 any suitable pipe (not shown) to communicate with the engine cylinder, and with the axial opening in the device.

One or more side passages 18 are provided extending from near the opening 10 to the face of the magnet and in each passage is a ball check 17 held in place by a spring 16 whereby air is prevented from entering the passage 10 when the valve 8^a is seated, and the armature spaced apart 80 from the magnet, and when the circuit is closed and the armature is drawn against the face of the magnet, the side opening 10 will be closed, thus preventing the exit of the compressed fluid through said passage, 85 when the valve 8^a is open.

This device is intended to be used on an internal combustion engine, in shunt circuit with the ignition circuits, whereby the magnet will be excited, and the valve 8^a opened 90 at the proper time for the compressed fluid to pass through the opening 10, and the pipe inserted therein, to the proper cylinder for starting the engine.

Upon the inspiration stroke of the engine, 95 the valve 8^a will be closed and the check valve 17 will prevent air from being drawn into the cylinder, and on the compression stroke, the valve 8^a will remain closed, and the check valve 17 will open and permit release of the compression through the passage 18 to aid in starting the engine. The device will thus operate to admit compressed fluid at the proper time to start the engine; will release the compression in the cylinders at 105 the proper time; will prevent the escape

of the compressed fluid used in starting the engine, and prevent admission of outside air on the inspiration strokes.

The engine is not herein shown, it being understood that this device is adapted to be used in connection with the ordinary internal combustion engine, for starting the same, the construction and operation of which is well known, to those familiar with such engines.

What I claim is:

1. An electrically operated valve, comprising a magnet having an axial opening therethrough and a side passage communicating with said opening, a valve to close said opening, an armature moved by the magnet and connected to the valve to open the same, and a check valve in said passage to prevent ingress of fluid and to permit fluid to escape.
2. An electrically operated valve, comprising a magnet having an axial opening therethrough and a side passage communicating with said opening and with the open air, a valve to close said opening, an armature to open the valve, a spring to hold the valve closed, and a check valve in the side passage to prevent ingress of fluid and to permit fluid to escape.
3. An electrically operated valve, comprising a magnet having an axial opening therethrough and a side passage communicating with said opening, a valve to close said axial opening, an armature to open said valve and simultaneously close the side passage, and a check valve in said passage to prevent ingress of air when the valve is closed.
4. An electrically operated valve, comprising a cylindrical magnet having an axial

opening and a side passage communicating with said opening and closed by the armature, a bolt in the axis of said opening, a valve on one end of the bolt to close said opening, a disk armature on the other end of the bolt to open the valve and close the passage, a spring to close the valve and move the armature away from the magnet, and a check valve in the passage to prevent ingress of air when the other valve is closed.

5. An electrically operated valve, comprising a magnet having an axial opening, a bolt in the axis of said opening, a valve on one end of the bolt to close the opening and a screw thread and a slot in the other end of the bolt, an armature having a screw threaded opening to receive the bolt, and a spring arm mounted on the armature and detachably engaging the slot.

6. An electrically operated valve, comprising a cylindrical magnet having an axial opening and a side passage communicating with said opening and opening opposite the armature, a valve seat in said opening, a removable ring to retain the seat in place, a bolt in the axis of the opening having a screw thread and slot at one end, a valve on the other end of the bolt engaging the seat and closing the axial opening, an armature adjustable on the threaded end of the bolt, a spring arm mounted on the armature and detachably engaging the slot in the bolt, and a check valve in the side passage.

In testimony whereof I affix my signature in presence of two witnesses.

WARREN W. ANNABLE.
